United States Patent Office

Des. 225,053
Patented Nov. 7, 1972

225,053

PANEL MEMBER FOR STORM AND SCREEN DOORS

Joseph F. Bovino, 1000 Jefferson Ave.,
Cherry Hill, N.J. 08034

Filed Dec. 24, 1969, Ser. No. 20,635

Term of patent 7 years

Int. Cl. D25—02

U.S. Cl. D13—1

The single figure is a front view of a panel member for storm and screen doors showing my new design, the rear being a mirror image thereof and the member being of conventional thickness.

I claim:

The ornamental design for a frame for a panel member for screen and screen doors, as shown and described.
